ARTICLE ARRANGING AND TRANSFER
MECHANISMRobert E. Wait, Hastings, Mich., assignor to
Hastings Manufacturing Company, Hastings,
Mich., a corporation of Michigan

Application January 3, 1949, Serial No. 68,998

7 Claims. (Cl. 198—24)

1

This invention relates to improvements in machines for feeding containers to a feed belt of a filling machine or the like.

The main objects of this invention are:

First, to provide a feed table for conveyers which permits the emptying of a carton of receptacles or containers upon the feed table and the alignment and delivery thereof to a conveyer belt without handling the containers and with little effort on the part of the operator.

Second to provide a feed table structure which may be readily adapted to filling machines and the like now in use.

Objects relating to details and economies of the invention will appear from the description to follow. The invention is defined and pointed out in the claims.

A preferred embodiment of the invention is illustrated in the accompanying drawing, in which:

Fig. 1 is a plan view of a structure embodying my invention, a plurality of containers being conventionally shown upon the table, conveyer, and in feed position.

Fig. 2 is a fragmentary view on a line corresponding to line 2—2 of Fig. 1.

Fig. 3 is a fragmentary view in section on a line corresponding to line 3—3 of Fig. 1.

In the accompanying drawing the frame of a filling machine or the like is indicated by the dotted lines 1 and a supporting rail or part is indicated at 2. The conveyer belt 3 is suitably supported with its upper reach traveling rearwardly or toward the filling machine to deliver containers shown conventionally at 4 thereto. When the containers are filled with liquid they are provided with spouts and filling closures which are not shown.

The feed table 5 is arranged with its top in the plane of the top reach of the belt 3 as shown in Fig. 3 and is recessed at 6 to receive the forward end of the belt. The rear side rails 7 of the conveyer extends forwardly beyond the front end of the belt to provide a rear work guide 8 for the table. The front conveyer side rail 9 terminates in substantially spaced relation to the front end of the belt and a stop bar 10 is mounted on the table transversely of the belt with its inner end adjacent the front end of the front rail 9.

The transfer slide 11 is slidably mounted by means of the slide rod 12 slidably in a bearing 13 so that the transfer slide is adapted by manual manipulation to push a row of containers transversely upon the belt and against the rear guide rail in which position they are picked up by the belt and carried to the filling machine. It is common practice for containers for liquid, which are commonly of tin, to be packed in cartons by the manufacturer for convenience in handling, a commercial size of such carton holding 24 containers. These are commonly packed with the

2

spouts downward so that when the carton is opened the containers may be discharged in upright position or if not thus packed the bottom of the carton is opened.

With the apparatus of my invention the carton of containers is discharged upon the table in advance of the front end of the belt as shown in Fig. 1 and they are ordinarily in a more or less irregular position as indicated. So far as applicant is aware it has heretofore been the practice for the operator to align these upon the table with the hands which required much handling and many motions. To facilitate alignment of the group of containers discharged upon the table, I provide an aligning or front guide bar 14 which is pivotally mounted at 15 to swing above the table, the pivot mounting 15 being positioned in alignment with the transfer slide 11 when it is in its retracted position as shown in Fig. 1. The swinging of this aligning or front guide bar to the position shown by dotted lines in Fig. 1, pushes the rear row of containers on the table against the rear guide rail 8.

With the containers thus positioned, the feed slide 16 is manually actuated, it being provided with a handle 17. This feed slide is slidably mounted on the slide rod 18 mounted on the table at the rear of the guide rail 8. The slide is slotted at 19 to receive the aligning bar or front side bar 14, the inner end of the slot 20 constituting a stop so that excessive pressure cannot be put on the containers. With the group of containers on the table thus aligned, the feed slide is operated and pushes the rear row of containers on the table endwise upon the belt and the other containers of the group are aligned against the stop bar 10 in front of the transfer slide 11 which is provided with a hand piece 21.

When the conveyer belt has translated the row of containers pushed endwise thereon to clear a space in front of the slide 11, the slide is actuated to push a row of containers transversely upon the belt and against the rear rail 7. This arrangement of parts enables an operator to keep the conveyer fully supplied with containers which is important as if the supply of containers to the filling machine is interrupted it is necessary to stop the filling machine or the filling mechanism and its cycle of operation is interrupted.

I have illustrated and described my invention in a highly practical embodiment thereof. The mechanism is simple and economical to produce and at the same time is efficient for the purpose.

Having thus described my invention, what I claim as new and desire to secure by Letters Patent is:

1. In a structure of the class described, the combination with a conveyer comprising a belt and rear and front side rails operatively associated therewith, of a feed table recessed to receive

the front end of said belt, the rear side rail projecting forwardly beyond the front end of the belt to provide a rear work guide for the table, the front side rail terminating in substantially spaced relation to the front end of the belt, a stop bar disposed transversely of the table at the front end of the front conveyer rail, a transfer slide mounted for reciprocation above the table in front of the stop bar and transversely of the belt to deliver work thereto, a feed slide mounted to reciprocate longitudinally of the table, and a front side bar pivotally supported at its rear end adjacent to and in substantial alignment with the transfer slide when it is in its retracted position, the said front side bar being swingable to facilitate placing work on the table and to facilitate the alignment thereof for advancement of the feed slide.

2. In a structure of the class described, the combination with a conveyer comprising a belt and rear and front side rails operatively associated therewith, of a feed table disposed at the front end of the belt and having a part extending at the front side thereof, a rear work guide for said table, the front side rail terminating in substantially spaced relation to the front end of the belt, a stop bar disposed transversely of the belt in spaced relation to its front end, a transfer slide mounted forward of the stop bar for reciprocation transversely of the belt to deliver work thereto, a feed slide mounted to reciprocate longitudinally of the table, and a front work guide for the table pivotally supported at its rear end in substantial alignment with the transfer slide when it is in its retracted position, the said front guide being swingable to facilitate placing work on the table and the alignment thereof for advancement by the feed slide.

3. In a structure of the class described, the combination with a conveyer comprising a belt and rear and front side rails operatively associated therewith, of a feed table disposed at the front end of the belt and having a part extending at the front side thereof, a rear work guide for said table, a stop bar disposed transversely of the belt in spaced relation to its front end, a transfer slide mounted forward of the stop bar for reciprocation transversely of the belt to deliver work thereto, a feed slide mounted to reciprocate longitudinally of the table, and a front work guide for the table pivotally supported at its rear end in substantial alignment with the transfer slide when it is in its retracted position, the said front guide being swingable to facilitate placing work on the table and the alignment thereof for advancement by the feed slide.

4. In a structure of the class described, the combination with a conveyer comprising a belt and rear and front side rails operatively associated therewith along the opposite sides thereof, of a feed table disposed at the front end of the belt and having a part extending at the front side thereof, a rear work guide for said table, the front side rail terminating in substantially spaced relation to the front end of the belt and to the front end of the rear side rail, a stop bar disposed transversely of the belt in spaced relation to its front end, a transfer slide mounted forward of the stop bar for reciprocation transversely of the belt to deliver work thereto forward the front end of the front side rail and in opposed relation to the rear side rail, a feed slide mounted to reciprocate longitudinally of the table.

5. In a structure of the class described, the combination of a feed table, a conveyer comprising a belt disposed with its rearwardly moving delivery reach in the plane of the table to receive work therefrom, a rear rail extending longitudinally of the table and positioned to align work for delivery to the front end of the belt, a stop bar positioned transversely of the belt in spaced relation to its front end, a transfer slide mounted forward of the stop bar and reciprocable transversely of the belt to deliver work supported by the table to the belt, a feed slide mounted to reciprocate longitudinally of the table, and an adjustable front work guide for guiding work to said transfer slide when it is in its retracted position and retractable to facilitate placing work on the table in advance of the feed slide.

6. The combination of a conveyer comprising a belt, a table disposed to extend forwardly of the forward end of the belt and at the side of the front portion of the belt, a rear conveyer side rail disposed at the rear of the belt and extending forwardly beyond the front end of the belt to constitute a work guide, a stop bar disposed transversely of the belt in spaced relation to its front end, a front conveyer rail disposed with its front end adjacent the inner end of said stop bar, a transfer slide mounted forward of the stop bar to reciprocate above the table transversely to the path of travel of the belt for transferring work from the table sidewise upon the belt, a feed slide, a slide way therefor mounted at the rear of the rear conveyer side rail, said feed slide being provided with a slot extending longitudinally thereof in its outer end, and a front work guide for the table pivotally mounted at its rear end adjacent the front end of the transfer slide when it is in retracted position, the front end of said front work guide being disposed through said slot in said feed slide, the inner end of which constitutes a stop.

7. The combination of a conveyer comprising a belt, a table disposed to extend forwardly of the forward end of the belt and at the side of the front portion of the belt, a rear conveyer side rail disposed at the rear of the belt and extending forwardly beyond the front end of the belt to constitute a work guide, a stop bar disposed transversely of the belt in spaced relation to its front end, a front conveyer rail disposed with its front end adjacent the inner end of said stop bar, a transfer slide mounted forward of the stop bar to reciprocate above the table transversely to the path of travel of the belt for transferring work from the table sidewise upon the belt, a feed slide, a slide way therefor mounted at the rear of the rear conveyer side rail, said feed slide being provided with a slot extending longitudinally thereof in its outer end, and an adjustable front work guide for the table having the front end thereof disposed through said slot.
